UNITED STATES PATENT OFFICE

1,930,864

AUTOMATIC FIREARM

Hugo Schmeisser, Suhl, Germany

Application March 5, 1932, Serial No. 597,052, and
in Germany March 9, 1931

5 Claims. (Cl. 42—1)

My invention relates generally to an automatic firearm and more particularly to that class of automatic firearms in which the barrel is adapted to slide lengthwise and a closing spring is accommodated in the neck of the stock.

The chief object of my invention is to provide a firing and safety mechanism in connection with a cartridge-delivering mechanism, which will be simple and compact in construction, efficient and reliable in operation and practical from both the stand-point of the manufacturer and the stand-point of the user.

The automatic guns for hunting and shooting purposes with a reciprocating barrel and rigid locking as hitherto known in the trade, are objectionable more or less for the reason that the firing and cartridge delivery-lever mechanism is actuated by means of flat springs or double-shanked bow-springs which are very liable to fracture so that in case of fracture the gun cannot be used and requires repair.

Guns of this type as hitherto constructed are also objectionable for the reason that the "safety" is provided at a least practical or handy place imaginable and a device indicating whether or not the gun is cocked, as usually in ordinary guns for hunting and shooting purposes, is not at all provided therein.

I shall now proceed to describe more in detail the improvements provided and advantages realized according to the present invention, with reference to the accompany drawing, the said improvements not only overcoming all disadvantages hitherto encountered in a firearm of this class, as above intimated, but also contributing to a more simple construction and less expensive manufacture than firearms of like general nature. In particular these advantages are secured by the provision of a pin carrying the hammer spring 40 and pivotally connected with the hammer and which, when the hammer is cocked, will project from the trigger guard to constitute a means for visibly indicating, that the hammer is in cocked position and the firearm ready for fitting, the 45 hammer in turn being held in cocked position by an upwardly extending hook-shaped front arm of the trigger member provided with an elongated, horizontal rear arm or trailing extension adapted to co-act with a safety member mounted in the 50 usual manner in the neck of the stock, and with a spring-controlled oscillating lever adapted to act on arresting surfaces of the cartridge delivering member or lever.

It will be seen that when the said rear arm 55 of the trigger member co-operates with the

safety member pushed rearwardly into "safe" position, the rear arm will be locked and consequently the trigger will also be locked against operation. Again, the provision of the improved hammer spring and safety mechanism involves the advantage of gaining sufficient room for the accommodation of a solid oscillating lever in lieu of the locking the cartridge delivery lever in the one (upper) or the other (lower) of its two positions.

In the accompanying drawing forming a part of this specification, and showing for purposes of exemplification, a preferred form and manner in which the invention may be embodied and practised,

Figure 1 is a fragmentary view in elevation, partly in section, of a firearm constructed according to the present invention, the safety mechanism being shown in "safe" position and the outer casing being indicated only by a contour line;

Figure 2 is a similar view showing the firearm in its uncocked and "unsafe" condition and the cartridge delivery lever in its fixed or arrested position with the free-lever end in slightly downward depending direction.

The trigger guard 2 is firmly attached to the lower side or bottom of the breech casing 1. In the frontal part of the latter, the hammer 4 is mounted on a transverse pin 3 so as to be capable of pivotal movement thereon. The rear face of the hammer is enlarged to form a lug for pivotal connection with a pin 5 partially housed in a bore of the trigger guard and surrounded by a coiled spring 6 wound about the pin 5 and partially accommodated in the said bore together with the pin. It will be seen that the upper part or end of the bore is widened to afford the necessary room for both the spring and the pin to move therein without any undue frictional contact with the wall of the bore, while the lower part or end 2a of the bore is of a reduced diameter to just allow of the pin to snugly fit and freely move therein in axial direction.

As shown in Figure 1 the lower end of the pin 5 projects beyond the end 2a of the bore when the hammer is in cocked position, for the purpose of visibly indicating the cocked condition of the firearm. It will be seen that thus the pin 5 forms a most reliable means of indication.

The trigger body 7 is elongated at the rear end to form a trailing arm 7a. When the safety slide 8 is put "safe", as shown in Figure 1, the

inner nose thereof will overlie the hook-shaped extremity of the trailing lever arm 7a so as to lock the trigger. The safety slide 8 may be of conventional construction. I prefer, however, to form the same of two parts which when assembled to embrace the tang 1a of the casing 1, constitute a unit adapted to be manually displaced on the tang a short way in both directions, as usually with safety devices of this class, 10 for locking the fire-arm to "safe" condition and releasing the same to "firing" condition, respectively.

By discarding the usual large flat hammer spring and substituting therefore a less cumbersome coiled spring I have gained ample room for the accommodation of an oscillating lever 9 pivoted at one end to the casing or any other suitable stationary part, and provided at its other or free end, with two oblique surfaces 20 10a and 10b for engagement with corresponding faces of the short or rear arm of the cartridge delivering lever 11. The lever 9 is controlled by a coiled spring 10 and it will be seen in Figure 2, that the lever faces 10a and 10b are adapted to contact with the corresponding faces of the short arm of the lever 11, that is to say, the face 10a will engage the one face of the short lever arm as shown in Figure 2, to arrest and lock the lever 11 in its lowermost 25 position, while the other face 10b will engage the opposite face of the short lever arm to arrest and lock the lever 11 in its uppermost position for purposes obvious to a man versed in the art.

I have not attempted to describe and show all of the details of the construction of the firearm because they will be self-suggesting to the man of the art and experts in firearms of this type will be able to supply all such details 40 in their correct design, proper in their size and relationship, properly mounted and supported according to the tenets of firearm construction. Nor does it seem necessary to burden this specification with an exposition of the advantages 45 which the invention possesses, for they will be apparent to those skilled in the art to which this invention pertains.

It is also apparent that in carrying out my invention some changes from the construction herein shown and described may be made. I would, therefore, have it understood, that I do not limit myself thereto, but hold myself at liberty to make such departures therefrom as fairly fall within the scope and spirit of my 55 invention.

What I claim is:—

1. In a firearm of the character referred to herein, the combination with a firing mechanism and a cartridge delivering member, of an indicating pin, a coiled spring wound about said pin, a bore in the trigger guard for the reception of said pin and spring, a hammer pivotally con-

nected to said pin, a safety of the sliding type, and a trigger member adapted to immediately catch the hammer and hold the same in cocked position against the resistance of said spring, the rear end of the said trigger member being enlarged to form an arm for co-operation with the safety.

2. In a firearm of the character referred to herein, the combination with a firing mechanism and a cartridge delivering member, of an indicating pin, a coiled spring wound about said pin, a bore in the trigger guard for the reception of said pin and spring, a hammer pivotally connected with said pin, a safety of the sliding type, a trigger member adapted to immediately catch the hammer and hold the same in cocked position against the action of the said spring, and a spring-controlled lever adapted to lock the said cartridge delivering member in one or the other of two positions, the rear end of the trigger body being extended to form an arm for co-operation with the said safety and the said spring-controlled lever.

3. In a firearm of the character referred to herein, the combination with a firing mechanism and a cartridge delivering member, an indicating pin, a coiled spring wound about said pin, a bore in the trigger guard for the accommodation of the said pin and spring, a hammer pivotally attached to said pin, a spring-controlled lever adapted to lock the said cartridge delivering member in one or the other of two positions, and a trailing arm for cooperation with the said spring-controlled lever.

4. In a firearm of the character referred to herein, the combination with a firing mechanism and a cartridge delivering member, of an indicating pin, a coiled spring wound about said pin, a hammer pivotally connected with said pin, a safety member, a trigger member adapted to immediately catch the hammer and hold the same in cocked position against the action of the said spring, and a spring-controlled lever adapted to lock the said cartridge delivering member in one or the other of two positions, the rear end of the trigger body being extended to form an arm for co-operation with the said safety member and the said spring-controlled lever.

5. In a firearm of the character referred to herein, the combination with a firing mechanism and a cartridge delivering member, of an indicating pin, a hammer pivotally connected with said pin, a safety member, a trigger member adapted to immediately catch the hammer and hold the same in cocked position, and a spring-controlled lever adapted to lock the said cartridge delivering member in one or the other of two positions, the rear end of the trigger body being extended to form an arm for co-operation with the said safety member and the said spring-controlled lever.

HUGO SCHMEISSER.
